(57) **CLAIM**

The ornamental design for a protective pad, as shown and described.

DESCRIPTION

FIG. 1 is a front perspective view of a protective pad from the upward, front, left side, showing a first embodiment of my new design;

FIG. 2 is a rear perspective view from the left side;

FIG. 3 is a front elevational view;

FIG. 4 is a rear elevational view;

FIG. 5 is a left side elevational view;

FIG. 6 is a right side elevational view;

FIG. 7 is a top view;

FIG. 8 is a bottom view;

FIG. 9 is a front perspective view of a protective pad from the upward, front, left side, showing a second embodiment of my new design;

FIG. 10 is a rear perspective view from the left side;

FIG. 11 is a front elevational view;

FIG. 12 is a rear elevational view;

FIG. 13 is a left side elevational view;

FIG. 14 is a right side elevational view;

FIG. 15 is a top view;

FIG. 16 is a bottom view;

FIG. 17 is a front perspective view of a protective pad from the upward, front, left side, showing a third embodiment of my new design;

FIG. 18 is a rear perspective view from the left side;

FIG. 19 is a front elevational view;

FIG. 20 is a rear elevational view;

FIG. 21 is a left side elevational view;

FIG. 22 is a right side elevational view;

FIG. 23 is a top view; and,

FIG. 24 is a bottom view.

Portions shown in dashed lines form no part of the claimed design.

1 Claim, 15 Drawing Sheets
